CONTACT SWITCH FOR ELECTRICAL
CONTACTS

Sydney Moledzky, Brooklyn, N. Y.

Application February 26, 1949, Serial No. 78,483

3 Claims. (Cl. 260—52)

1

This invention relates to a momentary contact switch for electrical contacts such as alarm systems and the like and has for its principal object the provision of such a switch which will be quick and sensitive in operation.

Another object of the present invention is the provision of such a switch which will be efficient in operation, inexpensive to manufacture and extremely simple in construction.

A still further object of the invention is the provision of such switch which when applied will permit the article to which it is applied to be left in such position that, while the switch would normally operate, it will remain inoperative.

Still another and further object of the invention is the provision of such a switch which may be readily adjusted to provide for sensitiveness with which it may operate under any desired condition in its use.

In the drawings accompanying and forming a part of this specification:

Figure 1 is a front elevation of the present improved switch shown attached and in operative position;

Fig. 2 is a side sectional view thereof taken on line 2—2 of Fig. 1;

Fig. 3 is a similar view to Fig. 2 illustrating the position of the parts when the article to which this improved switch is attached is left in an inclined position; and

Fig. 4 is a wiring diagram illustrating the switch in position in an alarm circuit.

Similar characters of reference indicate corresponding parts in the several views.

Before explaining in detail the present improvement and mode of operation thereof, it is to be understood that the invention is not limited to the details of construction illustrated in the accompanying drawings, since the invention is capable of other embodiments and only the principle thereof and the best mode, which has been contemplated, of applying that principle, has been set forth.

The present invention comprises a switch having a pair of swinging arms swingable in the same direction in the nature of pendulums carried by a fixed or stationary frame which is especially adaptable to be attached to a vehicle such as an automobile or truck and which will operate to sound an alarm if the vehicle is moved or jarred.

The switch mechanism comprises a frame member 2, of non-conductive material, having a base 4 and a pair of upstanding arms 6 and 8, the member 2 thus forming a U-shaped supporting frame.

2

This U-shaped member or frame 2 is adapted to be secured in any suitable manner at its base 4 to any suitable but inaccessible part of a vehicle.

At the top of this frame member 2 and extending through the upstanding arms 6 and 8 is a conducting rod 10 secured at either end thereof, by suitable nuts or fastening means 12, to the outer sides of the upstanding arms 6 and 8.

Supported centrally on this rod 10 and in engagement therewith is a swinging member 14 of conductive material which is adapted to swing or oscillate in pendulum fashion on the rod 10.

Also carried by this supporting rod 10 is a U-shaped member 16 of non-conductive material and of somewhat lighter construction than member 14, the upstanding arms of which lie between the arms 6 and 8 of the frame 2 and straddle the swinging member 14. Suitable bushings 18 are positioned along the rod 10 to separate the various parts and permit their free movement.

This U-shaped member 16 is also adapted to oscillate or swing in the manner of a pendulum on the shaft 10 in a direction similar to that of the member 14. Carried at its base the member 16 has a conductive U-shaped member 20, the upstanding arms of which straddle the base of the member 14 at right angles to the straddle of the arms of the member 16.

This member 20 is of very light material so that its upstanding arms may be easily bent to vary the clearance between them and the member 14 as desired. This member 20 likewise carries a very light wire connection 22 to the positive side of the power source. This connection is made with very light wire in order not to interfere with the free swinging action of member 16.

The rod 10 has a wire connection 24 to the negative side of the power source or ground.

In Fig. 4 a simple wiring diagram is illustrated in which it will be observed that a circuit leads from battery 26 through control switch 28, through wire 22 to the U member 20. Wire 22 likewise leads through wire 30 to one side of switch 32 and also through wire 34 through alarm 36 to one side of switch 38 connected in parallel with switch 32.

The ground or negative side of the battery 26 leads through wire 40 to the other side of switch 38 and through wire 42 through locking relay 44 through wire 46 to the other side of switch 32 and through wire 24 to conductive rod 10 and member 14.

The operation of the present improved switch is as follows:

The member 2 is secured in any suitable manner to a stationary part of a vehicle inaccessible.

to outside interference in such manner that it will permit the vehicle to be left standing at an incline either forward or backward and permit the two members 14 and 16 to swing in unison without making contact.

However, should the vehicle be suddenly jarred either by being run into or started the two arms will swing out of unison and cause a momentary contact to be made between conductive arm 14 and either upstanding arm of conductive member 20. This will cause a circuit to be established from the battery to locking relay 44 to pull down the arms of switches 32 and 38 and cause the alarm 36 to be sounded.

Even though the contact between members 14 and 20 is broken instantaneously the circuit once established will be held by the locking relay 44 until switch 28 is opened.

While there has been shown, described and pointed out the fundamental novel features of the invention, it is to be understood that various omissions, substitutions and changes may be made by those skilled in the art in the form and details of the device illustrated and in its operation without departing from the spirit of the invention. It is the intention, therefore, to be limited only as indicated by the scope of the following claims.

What is claimed is:

1. An electrical contact switch comprising a pair of members each supported for swinging movement relative to each other and means carried by each member for effecting an electrical contact upon a difference in swinging movement of one of said members relative to the other, each of said members having a common axis and located in the same plane, one having a pair of supporting arms and the other a single supporting arm located between said pair of supporting arms.

2. An electrical contact switch comprising a

pair of swinging members having a common axis and located in the same plane, one having a pair of supporting arms and the other a single supporting arm located between said pair of supporting arms, each of said members adapted to swing in unison and relative to each other and means carried by each member for effecting electrical contact upon a difference in swinging movement of one of said members relative to the other.

3. An electrical contact switch comprising a pair of swinging members having a common axis and located in the same plane, one having a pair of supporting arms and the other a single supporting arm located between said pair of supporting arms, each of said members adapted to swing in unison and relative to each other and means carried by each member for effecting electrical contact upon a difference in swinging movement of one of said members relative to the other, the contact means of one of said members effective to effect contact with the other upon said relative difference in swinging movement in either direction.

25 SYDNEY MOLEDZKY.
